UNITED STATES PATENT OFFICE.

ALBERT MARTIN DAVIS, OF MADISON, WISCONSIN.

BINDER ATTACHMENT.

SPECIFICATION forming part of Letters Patent No. 764,431, dated July 5, 1904.

Application filed September 19, 1903. Serial No. 173,822. (No model.)

To all whom it may concern:

Be it known that I, ALBERT MARTIN DAVIS, a citizen of the United States, and a resident of Madison, in the county of Dane and State 5 of Wisconsin, have invented a new and Improved Binder Attachment, of which the following is a full, clear, and exact description.

The object of this invention is to decrease the friction attending the formation of the 10 gavel in a self-binding harvester of any sort and also to assist in separating the bundle from the unbound grain.

To this end the invention comprises an improved breastplate, the principal feature of 15 which is one or more traveling members, such as chains, mounted on the breastplate and arranged to run freely under the action of the moving grain, thus relieving the binder of the friction which takes place during the 20 operation of the ordinary binder. With this breastplate is associated a dog or stop device which holds the grain firmly in place under the breastplate and against the trip-arm, and on the deck of the binder I form a shoulder 25 lying just under the breastplate and facing the trip-arm, the binder-deck having an incline leading up to this shoulder, so that the grain is forced up along the incline and over the shoulder during the formation of the 30 gavel. This shoulder and incline not only hold the grain firmly in place against the trip-arm, but they relieve the needle and packers of considerable work, thereby enabling the binder to be run more readily than ordinarily. 35 This specification is an exact description of one example of my invention, while the claims define the actual scope thereof.

Reference is to be had to the accompanying drawings, forming a part of this specification, 40 in which similar characters of reference indicate corresponding parts in all the views.

Figure 1 is a side elevation of my invention. Fig. 2 is a top plan view of the breastplate. Fig. 3 is a bottom plan view, the chains being removed. Fig. 4 is a section on the line 44 of Fig. 1. Fig. 5 is a section on the line 55 of Fig. 1, and Fig. 6 is a section on the line 66 of Fig. 1.

10 indicates the binder-deck, 11 the needle, 50 12 one of the packers, and 14 the trip-arm,

all of which may be of the usual or any desired construction.

The breastplate comprises an upper portion 15, from which extend two oblong chain-guides 16, spaced from each other to form a 55 passage 17 for the needle. Said upper portion 15 has a cavity 18 in its under side, this cavity forming a continuation of the needle-cavity 17. The lower portion 19 of the breastplate is formed integral with the chain-guides 60 and has a cavity 20 therein forming a continuation of the cavity 17, through which cavity 20 the knotter device is worked.

21 indicates guide-flanges or guards formed on the under side of the lower part 19 of the 65 breastplate at each side of the chain-guides 16 and serving to prevent the straw from passing up with the chains. The chains 22 are endless and are arranged to run freely around the chain-guides, the bottom runs of 70 the chains lying directly over the deck of the binder, and said chains have the gavel pressed toward them. As the grain moves toward the trip-arm in the formation of the gavel the chains move with the grain, and thus the friction of the grain moving against the breastplate is greatly reduced. 75

Brackets 23 are attached to the upper portion 15 of the breastplate and project transversely from each side thereof. Said brackets have pivotally mounted thereon the arms or levers 24, the lower portions of which have teeth 25 formed on or fastened thereto and the upper portions of which are connected by a cross-piece 26, to which springs 27 are applied, these springs tending to throw down the lower ends of the arms 24. These toothed arms bear, therefore, on top of the gavel during the formation thereof, and while they offer practically no resistance to the movement 80 of the grain toward the trip-arm they nevertheless effectively prevent the return thereof. 85

According to the construction here shown I fasten on the deck of the binder a number of transversely-alined cleats 28, which have 95 their upper edges 28^a slanting from the deck-line upward to their rear edges 28^b. Said edges 28^a form, therefore, an incline leading up to the lower edges 28^b to form a shoulder facing the trip-arm 14. This shoulder and 100

incline may be formed by other means, if desired; but I consider the construction above described preferable, since it is light and reduces the friction on the moving grain. As 5 the grain is advanced by the packers it is pushed along the incline and finally drops down in front of the shoulder, which holds the grain snug and prevents the return thereof, this shoulder then coacting with the dog- 10 arms 24. This shoulder also completely separates the gavel from the unformed grain on the upper part of the deck, and when the bun- 15 dle is formed it may be readily discharged from the machine, the discharge being in this case much easier and freer than heretofore. Further and of equal importance is the fact that the incline holds the grain up from the plane of the deck at the point where the needle passes through, and thus the needle is al- 20 lowed to assume nearly a vertical position before its heel strikes the grain. This greatly relieves the needle and causes the grain to be forced downward toward the trip-arm instead of upward against the breastplate.

25 Various changes in the form, proportions, and minor details of my invention may be resorted to at will without departing from the spirit and scope thereof. Hence I consider myself entitled to all such variations as may 30 lie within the intent of my claims.

Having thus described my invention, I claim as new and desire to secure by Letters Patent—

1. A binder-breastplate, having a member mounted to slide freely thereon and adapted 35 to be engaged by the grain, for the purpose specified.
2. A binder-breastplate, having an endless chain arranged to run free thereon and to be engaged by the grain, for the purpose speci- 40 fied.
3. A binder-breastplate, comprising an oval guide, and an endless chain arranged to run

free around the same and to be engaged by the grain.

4. A binder - breastplate, comprising two 45 chain-guides spaced from each other to receive the needle, and a chain arranged to run free on each guide and adapted to be engaged by the grain, for the purpose specified.

5. In a binder, the combination with the 50 breastplate, of a yieldingly-sustained arm at each side thereof, said arms having teeth thereon and forming dogs to prevent the return of the grain.

6. In a binder, the combination of a yield- 55 ingly-sustained dog arranged to bear on top of the gavel, and a binder-deck having a trans- verse shoulder formed thereon and facing the trip-arm.

7. In a binder, the combination of a breast- 60 plate, a member arranged to run free thereon and adapted to be engaged by the grain, for the purpose specified, and a yieldingly-sus- tained arm on each side of the breastplate, said arms having teeth thereon adapted to en- gage the gavel to prevent the return thereof.

8. In a binder, the combination of a breast- 65 plate, a member arranged to run free thereon and adapted to be engaged by the grain for the purpose specified, a yieldingly-sustained 70 dog arranged at each side of the breastplate and adapted to bear on top of the gavel, and a deck located under the dog and breastplate and having a transverse shoulder thereon fac- 75 ing the trip-arm and forming with the trip- arm a receptacle for the gavel.

In testimony whereof I have signed my name to this specification in the presence of two sub- scribing witnesses.

ALBERT MARTIN DAVIS.
